UNITED STATES PATENT OFFICE

132,182

DESIGN FOR AN AIR CONDITIONING UNIT

Frederick M. Jones, Minneapolis, Minn., assignor
to U S Thermo Control Company, an associa-
tion composed of Joseph A. Numero and M.
Green

Application April 10, 1941, Serial No. 100,294

Term of patent 14 years

To all whom it may concern:

Be it known that I, Frederick M. Jones, a citizen of the United States, residing at Minneapolis, in the county of Hennepin and State of Minnesota, have invented a new, original, and ornamental Design for an Air Conditioning Unit, of which the following is a specification, reference being had to the accompanying drawings, forming part thereof.

In the drawings:

Fig. 1 is a perspective view showing the top and rear of an air conditioning unit embodying the design of my invention.

Fig. 2 is a perspective view showing the rear, top and left side thereof.

Fig. 3 is a perspective view showing the front, top, and left side thereof.

The right hand side is substantially the same as the left side which is shown.

I claim:

The ornamental design for an air conditioning unit, as shown and described.

FREDERICK M. JONES.
